GATE CLOSURE

Maxwell F. Kemper, Los Angeles, Calif.

Application September 17, 1940, Serial No. 357,122

3 Claims. (Cl. 220—46)

This invention relates to closures and more particularly to pneumatic seals for gates or covers for containers requiring sealing to maintain pressure therein, for example for pneumatic concrete discharge "guns" or conveyors.

The principal object of the invention is to provide an effective air tight seal for closures for containers and especially to provide a pneumatically actuated seal for apparatus which is itself pneumatically actuated.

In the handling of plastic and granular materials, it is common to convey them by air pressure. In many cases where mixed wet concrete is employed it is conducted to places of deposit, such as tunnel lining, by blowing from a sealed container or pressure chamber by apparatus often known as a concrete gun. After a receiving chamber or hopper has been filled with the mixed concrete, the inlet opening at the top must be tightly sealed, in order that the concrete may be pneumatically discharged from the bottom of the hopper without appreciable loss of pressure through the filling opening. It is desirable therefore to actuate the closure for the vessel pneumatically and to seal it pneumatically, and the present invention performs these functions. Other materials may be handled with the same apparatus.

The present invention comprises a closure plate or cover having a contact face around its periphery on its under side adapted to cooperate with a corresponding contact face around the periphery of the opening of the vessel to be sealed. One of these members, preferably the closure plate, contains a movable or expandible element, preferably a pneumatically actuated element such as an inflatable gasket, adapted to be moved into sealing engagement with the other member when the members have been secured in sealing relation. In a preferred embodiment the closure plate is slidably mounted to move to and from closing position, and this motion preferably is pneumatically effected. Also in a preferred embodiment, the closure plate possesses a peripheral recess or groove in its contacting face which receives an expandible rubber gasket having a continuous air cavity rendering the gasket inflatable by air pressure to expand the gasket into sealing contact with the contact face of the closure member on the vessel itself. In the slidable form of closure, a scraping blade may be provided on the advancing edge of the closure to clear away material deposited on the contact face of the vessel.

In the accompanying drawing wherein certain embodiments of the invention are disclosed by way of illustration,

Fig. 1 is a vertical sectional view of a container equipped with the present closure, the section being taken approximately on the line 1—1 of Figure 2;

5 Fig. 2 is a plan view with portions broken away;

Fig. 3 is a vertical sectional detail showing the forward edge of a slidable closure plate approaching closed position;

10 Fig. 4 is a vertical sectional detail on line 4—4 of Figure 2, the sealing gasket being in deflated condition;

Fig. 5 is a vertical sectional detail showing the sealing gasket in inflated sealing condition; and

15 Fig. 6 is a cross sectional detail through the valve controlling the movement of the closure plate.

20 In these drawings a vessel 10 adapted to be sealed is shown as provided with a filling neck 11 having a circular opening. This neck is provided with a flange 12 whose upper face constitutes a contact or sealing face which is rectangular at its periphery and carries two rearwardly extending legs or sections 12'.

25 A closure plate 15 is adapted to make sealing contact with said contact face 12, and in the form shown is a sliding plate which is square as shown and has its sides extending beyond the sides of the contact flanges 12 and has secured thereto by means of machine screws 16 guide members 17 whose extensions 17' engage under the lower edges of flange 12 to confine plate 15 to flange 12.

30 The lower face of the peripheral portion of the closure plate 15 is provided with a continuous groove 18 which in the present form is annular and is of dove-tailed shape whereby to retain an annular rubber gasket G. This gasket G in its normal or deflated condition has a web section which arches up into the groove so that it will be in non-sealing contact with any adjacent face. 35 It is provided with side walls which engage the sides of the groove and have overhanging lips which, however, do not contact each other thereby providing an annular cavity open along its median line whereby to receive or discharge air under pressure supplied through a duct 20 in the plate 15 which duct is connected at 21 with flexible airhose 22 supplied from a supply line 5.

40 The sliding or reciprocating action of plate 15 is accomplished through the medium of a pair of cylinders 25 secured to vessel 10 each of which contains a piston 26 having a piston rod 27 extending through a packing gland 28, the outer ends of said piston rods being secured at 29 to 45 ears 30 secured near the forward or advancing

edge of plate 15. The pistons 26 are reciprocated within the cylinders 25 to advance plate 15 to closed portion or withdraw it to open portion by means of high pressure air from air lines 32 and 33 leading to opposite ends of each cylinder 25 and controlled through the medium of valve V. These lines 32 and 33 are supplied from a main air supply line S which feeds the valve V. The rotary element 34 of valve V divides the central air chamber so that air may be passed from supply line S either to the lines 32 or to the lines 33. In the position shown the air is being supplied from line S to lines 32 to retract the pistons 26 to open the gate or plate 15. The air in lines 33 and in the cylinders 25 is being vented by way of an adjustable vent valve 35 secured to the valve body V and including an adjustable cap having vent ports 36 and a control needle 37 co-operating with a bleeding port 38 in the member 35. By this adjustable venting or bleeding means the rate of travel of the gate 15 to and from closed position is cushioned and regulated as desired.

Air from the supply line S is also conducted by way of a second valve 40 through the flexible line or hose 22 to the air duct 20 in the plate 15 and thence to the annular channel or cavity in gasket G. The flexible hose 22 permits the gate 15 to pass through its reciprocating movements.

In operating this invention, the gate or closure plate 15 will be placed in retracted or open position on the legs 12 by the adjustment of the valve V to the position shown whereby the pistons 26 will be caused to travel in the cylinders 25 to the right, the air in the said cylinders being vented through the lines 33 and ports 38 and 36 in vent valve 35. Under these conditions the valve 40 will have been adjusted so that the pressure in the flexible line 22 and the gasket G will have been vented through a port contained in a vent nozzle 42 or the like. When the plate 15 has been moved to such retracted position the vessel 10 may then be filled with appropriate materials such as wet mixed concrete, whereupon valve V will be adjusted to admit air to the lines 33 and right ends of the cylinders 25 thereby forcing the pistons 26 to the left and causing the closure plate 15 to move into the closed position indicated in Figures 1 and 2. Under these conditions the gasket G is deflated, by reason of the fact that valve 40 is in closed position, and the exposed face or web of said gasket G assumes the arched position shown in Figures 3 and 4, this position constituting the retracted position of the gasket G. When the gasket G is in this condition the plate 15 may be readily reciprocated without contact between the exposed face of gasket G and portions of the stationary contact faces 12 of the flanged filling neck 11.

The forward or advance edge of plate 15 is preferably equipped with a hardened scraper blade B which may be removably secured as by means of set screws 45. This blade continuously travels in contact with the contact faces 12 and thereby scrapes away any materials which may have accumulated upon said faces in the filling operation. Thus, when the plate 15 has reached

its closed position, the contact faces 12 are clean and in condition for sealing. Sealing is now effected by opening the valve 40 thereby passing air through the flexible line 22 by way of connection of 21 and duct 20 into the annular channel within the gasket G. This high pressure air forces the exposed contact face of gasket G outward and downward against the contact faces 12 of the flanged filling neck 11 and expands the side walls of gasket G against the side walls of said dove-tailed groove 18, and forces the bottom of gasket G against said contact faces 12. This places the chamber 10 in sealed condition for applying high pressure thereto as in the case of expelling the contents of the chamber pneumatically from a discharge throat at the bottom thereof.

It will be obvious to those skilled in the art that modifications may be made within the scope of the appended claims.

I claim:

1. A closure for a materials inlet opening leading to a receiving chamber subject to high internal pressure comprising, a cover plate mounted for movement to close the mouth of the opening, a gasket on said cover plate expandible in a direction axially of the mouth of the opening forming a seal between the cover plate and the mouth of the opening, means limiting movement of said cover plate axially of the mouth of the opening, and a passage communicating with said gasket permitting the application of a pressure on the gasket sufficient to cause expansion of the gasket to seal the joint between the cover plate and the mouth of the opening.

2. A closure for a materials inlet opening leading to a receiving chamber subject to high internal pressure comprising, a cover plate mounted for movement transversely of the mouth of the opening into registry with the opening, said opening having a sealing surface disposed transversely of its axis, a scraper movable in contact with said sealing surface in advance of the plate upon closing movement of the plate, a gasket on said cover plate expandible in a direction axially of the mouth of the opening forming a seal between the plate and the sealing surface of the opening, and a passage communicating with said gasket permitting the application of a pressure on the gasket sufficient to cause expansion of the gasket to seal the joint between the cover plate and the mouth of the opening.

3. A closure for a materials inlet opening leading to a receiving chamber subject to high internal pressure comprising a cover plate mounted for movement transversely of the mouth of the opening into registry with the opening, said opening having a sealing surface disposed at its mouth, and said cover plate sliding along said sealing surface, a gasket on said cover plate expandible in a direction axially of the mouth of the opening forming a seal between the plate and the sealing surface of the opening, and a passage communicating with said gasket permitting the application of a pressure on the gasket sufficient to cause expansion of the gasket to seal the joint between the cover plate and the mouth of the opening.

M. F. KEMPER.
